UNITED STATES PATENT OFFICE.

EDWARD S. KARSTENS, OF DAVENPORT, IOWA.

CYLINDER-LAPPING TOOL.

Application filed September 25, 1922. Serial No. 590,490.

To all whom it may concern:

Be it known that EDWARD S. KARSTENS, a citizen of the United States, residing at Davenport, in the county of Scott and State of Iowa, has invented certain new and useful Improvements in Cylinder-Lapping Tools, of which the following is a specification.

My invention relates to improvements in appliances for lapping in cylinders of internal combustion engines and similar uses and may also be used for grinding such cylinders.

The objects of my invention are, first, to provide a cylinder lapping tool which can be utilized for grinding L-head and T-head motors with a head cast integral with the cylinder block; second, to provide a cylinder lapping tool for grinding valve-in-head cylinders where there is a very small clearance at the head end of the cylinder; third, to provide means by which the blocks of abrasive material in the lapping tool are firmly held and to control the feed of such blocks and maintain the blocks parallel to the longitudinal axis of the body of the lapping tool and to provide for a graduated feed of such blocks.

I attain these objects by the mechanism illustrated in the accompanying drawings, in which,—

Figure 1 represents a side elevation of my lapping appliance showing the upper half thereof in section on the middle line; Fig. 2 is a plan view of one of the stoneholders; Fig. 3 is a side elevation of one of the stoneholders; Fig. 4 is an end elevation thereof; Fig. 5 is a longitudinal section of the adjusting screw; Fig. 6 is an end view of the adjusting screw; Fig. 7 is an end view of the larger end of the body of the tool with the stoneholders and inner collar removed; Fig. 8 is an end view of the inner collar and front end of the appliance; Fig. 9 is a side elevation of the inner collar showing the bevelled face in dotted lines; Fig. 10 shows a side elevation of the rear or exterior collar with the inner lines thereof shown in dotted lines; Fig. 11 is an inner end view of the external collar; Fig. 12 is a plan view and Figure 13 is a longitudinal section of the spring.

I refer to the right end of Figure 1 as the front end of the appliance and the left

end of Figure 1 as the rear end of the appliance.

Similar numerals refer to similar parts throughout the several views.

The body of my device comprises a tapered shank, 1^a, with a body portion, 1, formed integral therewith.

The body is cylindrical, but has a plurality of longitudinal channels, 5, cut or otherwise formed in it. The front end of the body is bevelled or tapered to correspond to the internal bevel or taper of the front collar, 6, which is a circular collar surrounding the shank and smaller end of the body of the appliance and may be secured in place by set screws as shown in Figure 10 or otherwise.

Stoneholders, 2, corresponding in width and length to the channels, 5, are seated in said channels. The rear end of each stoneholder, 2, is shaped to correspond with the internal taper of the collar, 6. The rear end of each stoneholder has an outwardly projecting portion corresponding in height to the outwardly projecting portion at the front end and the internal faces of these projecting portions are bevelled to enable them to retain the grinding or lapping stones, 3. The front end of each stoneholder also has an inwardly projecting portion, 12, formed integral therewith, although slightly narrower than the outer portion and the inwardly projecting portion, 12, has its inner face bevelled or tapered to correspond to the bevel or taper of the face, 11, of the rear end of the stoneholder, but with this difference, that the face of the rear end, 11, is curved laterally to fit the internal taper of the collar, 6, while the bevelled face of the projecting portion, 12, is preferably made flat to fit a corresponding flat-bottomed channel, 15, in the side of the internal collar, 14.

The channel, 5^a, is formed in the inwardly projecting portion, 12, of the front end of each stoneholder adapted to receive a head, 8, of an adjusting screw, 7.

The adjusting screw, 7, is threaded to fit into a threaded central opening in the body, 1, and the threaded screw, 7, is preferably formed with a hexagonal key seat, 9, formed in the head end thereof adapted to receive a key by which the screw, 7, can be turned. As the screw, 7, is turned, the head, 8, act-

ing in the channels, 5^a, carries the stoneholders, 2, with the screw, 7, and as the bevels, 11 and 12, correspond, the stoneholders and the lapping stones secured therein, are carried toward the center of the body when the screw is turned in one direction and when turned in the opposite direction, the stoneholders are pressed outwardly by the flat springs, 4, one of which 5 is mounted in each channel, 5, of the body of the tool. A pin, 17, is secured in a closely fitting hole or opening in the middle of each stoneholder adapted to enter a corresponding opening, 18, in the middle of the 10 adjacent spring, 4.

I have shown a flat spring in the drawings as my preferred form, having its ends bearing against the stoneholder near the ends thereof and its middle portion bearing 20 against the bottom of its corresponding channel, 5, but it is obvious that other forms of springs may be used to effect the same purposes.

The front end of the body, 1, is provided 25 with a circular opening large enough to receive the collar, 14, and a small space is left between the threaded screw, 7, and the surrounding portions of the inwardly extending ends of the stoneholders, 2.

30 In a lapping appliance adapted to grind or lap cylinders of approximately three inches in diameter, I prefer to provide sufficient space for inward and outward movement of the stoneholders of approximately 35 three-eighths of an inch, but this space may be varied to suit the requirements of each particular case and to meet requirements for different sized cylinders, it being preferable to have a number of lapping tools to correspond to different standard sizes of cylinders rather than to allow too large a limit of adjustment for each particular tool.

In the operation of my device, the shank, 1^a is mounted in the tool holder of an engine lathe, boring mill or other suitable machine. The cylinder to be lapped or ground is then adjusted to the desired diameter and the work proceeded with in the ordinary way.

50 The lapping stones may be varied in granular structure to meet the requirements of each particular case. Where a large amount of material is to be taken out, it is preferable to use coarser stones for the first cut or two and if desired, stones may be used of such a fine grain as to merely true up and polish the interior of the cylinders without effecting any material cutting away of stock.

It is obvious that my device may be used 60 for either wet or dry grinding, but for many classes of work, I prefer to use oil as it will procure a smoother cut and finish than could otherwise be obtained.

In practice, I prefer to secure the stones 65 in place in the stoneholders by leading them

in, but it is obvious that they may be secured in place by any other suitable means.

The size and proportions of my appliance may be varied to meet the requirements of each particular case without departing from 70 the spirit of my invention. In the case of large cylinders, where there is sufficient room, the number of channels and stoneholders may be increased and in smaller sized cylinders, it may be reduced to three or 75 two if desired. The collar, 14, may be formed integral with the body, 1, but is easier to manufacture if formed separately.

I claim:

1. In a lapping tool a cylindrical body 80 having a shank at one end formed integral therewith, an internally tapered collar secured to the body adjacent the shank, a cylindrical seat formed in the opposite end of the body and a collar seated therein tapered internally at an angle to correspond 85 to the internal taper of the collar adjacent the shank and stoneholders having extensions engaging the collars with tapers corresponding to the taper of the collars.

2. In a lapping tool a cylindrical body having a shank at one end formed integral therewith, an internally tapered collar secured to the body adjacent the shank, a cylindrical seat formed in the opposite end of the body and a collar seated therein tapered internally at an angle to correspond 90 to the internal taper of the collar adjacent the shank and stoneholders having extensions engaging the collars with tapers corresponding to the taper of the collars, said 95 stoneholders being secured in longitudinal channels formed in the body of the appliance.

3. In a lapping tool a cylindrical body 100 having a shank at the end formed integral therewith, an internally tapered collar secured to the body adjacent the shank, a cylindrical seat formed in the opposite end of the body and a collar seated therein tapered internally at an angle to correspond 105 to the internal taper of the collar adjacent the shank, stoneholders having extensions engaging the collars with tapers corresponding to the taper of the collars, an adjusting screw threaded into a longitudinal opening in the center of the body and means 110 for transmitting the longitudinal motion of the adjusting screw to the stoneholders.

4. In a lapping tool a cylindrical body 115 having a shank at one end formed integral therewith, an internally tapered collar secured to the body adjacent the shank, a cylindrical seat formed in the opposite end of the body and a collar seated therein tapered internally at an angle to correspond 120 to the internal taper of the collar adjacent the shank, stoneholders having extensions engaging the collars with tapers corresponding to the taper of the collars and an adjusting 125 screw.

screw threaded into a longitudinal opening in the body of the appliance and having a head projecting into the grooves or channels formed in inwardly projecting portions of the stoneholders.

5. In a lapping tool a cylindrical body having a shank at one end formed integral therewith, an internally tapered collar secured to the body adjacent the shank, a cylindrical seat formed in the opposite end of the body and a collar seated therein tapered internally at an angle to correspond to the internal taper of the collar adjacent the shank, stoneholders having extensions engaging the collars with tapers corresponding to the taper of the collars, said stoneholders being secured in longitudinal channels formed in the body of the appliance and a spring seated in the bottom of each channel 20 with its ends bearing against the holder and its intermediate portion bearing against the body.

6. In a lapping tool, a cylindrical body having a shank at one end formed integral therewith, an internally tapered collar secured to the body adjacent the shank, a cylindrical seat formed in the opposite end of the body and a collar seated therein tapered internally at an angle to correspond to the internal taper of the collar adjacent the shank, stoneholders having extensions engaging the collars with tapers corresponding to the taper of the collars, said stoneholders being secured in longitudinal channels formed in the body of the appliance, an adjusting screw threaded into a longitudinal opening in the center of the body, means for transmitting the longitudinal motion of the adjusting screw to the stoneholders, and a spring seated in the bottom of each channel with its ends bearing against the holder and its intermediate portion bearing against the body.

7. In a tool for lapping and grinding cylinders, the combination with a plurality of abrasive blocks mounted in suitable holders, of projecting ends formed upon said holders carrying similarly tapered portions, said holders being secured in longitudinal channels formed in the body of the appliance, collars secured at each end of the body having internally tapered faces corresponding to the tapered portions of the holders, an adjusting screw threaded into a longitudinal opening in the body of the appliance and means operatively connecting the adjusting screw with the holders.

8. In a tool for lapping and grinding cyl-

inders, the combination with a plurality of abrasive blocks mounted in suitable holders, 60 of projecting ends formed upon said holders carrying similarly tapered portions, said holders being secured in longitudinal channels formed in the body of the appliance, collars secured at each end of the body of the appliance having internally tapered faces corresponding to the tapered portions of the holders, an adjusting screw threaded into a longitudinal opening in the body of the appliance, means operatively connecting 65 the adjusting screw with the holders, a spring seated in the bottom of each channel with its ends bearing against the adjacent holder and its intermediate portion bearing against the body, and a pin or lug securing 70 each spring to its adjacent holder.

9. In a tool for lapping cylinders, the combination with a plurality of stoneholders, each stoneholder having one end tapered longitudinally and its opposite end provided with an inward extension carrying a similarly tapered portion, of collars secured to the body of the tool and having internally tapered faces corresponding to the tapered portions of the stoneholders, means for adjusting the position of the stoneholders longitudinally upon the tapered faces of the collars and a plurality of springs mounted upon the body of the tool bearing outwardly 80 against the stoneholders respectively.

10. In a cylinder lapping and grinding appliance, the combination with a body having an internally tapered seat formed therein and an internally tapered collar portion secured thereto, of stoneholders carrying projecting portions tapered to correspond with the tapers of the seat and collar and adapted to engage the seat and collar respectively, and means for sliding the stoneholders longitudinally upon the tapered portions thereof.

11. In a cylinder lapping and grinding appliance, the combination with a body having an internally tapered seat formed therein and an internally tapered collar portion secured thereto, of stoneholders carrying projecting portions tapered to correspond with the tapers of the seat and collar and adapted to engage the seat and collar respectively and means for sliding the stoneholders longitudinally upon the tapered portions thereof and securing them at any desired point.

In testimony whereof he affixes his signature.

EDWARD S. KARSTENS.
